UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

APPARATUS FOR CONDENSING STEAM AND HEATING FEED-WATER.

1,375,977.

Specification of Letters Patent. Patented Apr. 26, 1921.

Application filed September 26, 1918. Serial No. 255,817.

To all whom it may concern:

Be it known that I, FREDERICK SAMUELSON, a subject of the King of Great Britain and Ireland, residing at Rugby, county of Warwickshire, England, have invented certain new and useful Improvements in Apparatus for Condensing Steam and Heating Feed-Water, of which the following is a specification.

10 The present invention relates to power systems in which steam exhausting from a prime mover or extracted from a region of intermediate pressure therein is used to supply heat to the feed water which is supplied 15 to the steam generator.

20 The object of the invention is to provide an improved system of the above referred to character, and for a consideration of what I believe to be novel and my invention, attention is directed to the accompanying specification and the claims appended thereto.

25 In the drawing, Figure 1 is a diagram of a system embodying my invention; Fig. 2 is a sectional view on a larger scale than Fig. 1 of a valve mechanism which forms a part of the system, and Fig. 3 is a longitudinal sectional view of a heat exchange device.

30 Referring to the drawing, 5 indicates a prime mover here shown in the form of a steam turbine provided with an inlet conduit 6 which may lead from a suitable steam generator and an exhaust conduit 7 which leads to a condenser 8. Condensate is removed 35 from the condenser 8 by a pump 9 which draws the condensate off through a conduit 10 and delivers it through a conduit 11 to a feed water heater 12. The feed water heater is constructed after the manner 40 of a surface condenser being provided with tubes 13 carried by end plates 14 and communicating with end chambers 15 and 16 formed by heads 17 and 18. End chamber 16 is divided by a partition 19 into upper 45 and lower chambers, 16^a and 16^b, conduit 11 communicating with the lower chamber 16^b. Leading from the upper chamber 16^a is a conduit 20 which carries away the heated feed water and which may lead to a boiler 50 or hot well as indicated at 21. With this arrangement it will be seen that the condensate is fed from chamber 16^b through the lower portion of the tubes 13 to chamber 15, thence through the upper portion of tubes

13 to conduit 20. Steam is led from an intermediate stage of the turbine 5 to the feed water heater 12 by a conduit 22 provided with a suitable valve 23 and here it gives up its heat to the condensate from condenser 8 and is itself condensed. The condensate from the heating steam is led to condenser 8 by conduits 24 and 25 between which is a valve 26 having a hollow stem 27 which extends into a float chamber 28. Float chamber 28 is connected by a conduit 29 to the upper portion of feed water heater 12 and by a conduit 30 to conduits 24 and 25. In float chamber 28 is a float 31 connected to the valve stem 27.

55 In operation condensate from condenser 8 is pumped through tubes 13 of the feed water heater flowing first through the lower portion of them and then through the upper portion as already referred to, and at the same time sufficient steam is admitted 60 through conduit 22 to heat the feed water to the desired temperature. Such steam enters at the top of the feed water heater and condenses therein, giving up its heat to the condensate flowing through tubes 13. Because 65 of the float controlled valves 26 the condensate in the feed water heater will assume and be maintained at a level as shown in Figs. 1 and 3. As steam condenses in the feed water heater raising the level therein, the 70 float 31 will open valve 26 to permit condensate to flow out through conduits 24 and 25 to condenser 8 from which it will be removed by pump 9 along the condensate from the turbine 5. The desired level of 75 water in the heater 12 will always be maintained, however. Cold condensate pumped from condenser 8 first passes through the tubes 13 in the lower portion of the feed water heater. These tubes are surrounded 80 by condensate of the heating steam which is already partially cooled and in passing through such tubes the condensate from condenser 8 further cools the surrounding condensate of the heating steam so that when 85 such surrounding condensate is discharged through valve 26 it is at a comparatively low temperature. As the condensate from condenser 8 passes through the tubes 13 in the upper portion of the heater 12 it passes 90 through tubes 13 surrounded by hotter condensate and by steam and hence is heated 95 to the desired temperature before it passes 100 through tubes 13 surrounded by hotter condensate and by steam and hence is heated 105 to the desired temperature before it passes

to conduit 20. By this arrangement the heat of the steam taken from the prime mover is efficiently utilized in heating the feed water and such steam is condensed and cooled prior to its passage to the condenser 8. Due to this when the condensed steam which has been used for heating passes to the condenser 8, it is sufficiently cooled that it does not re-evaporate and thus impair the 10 vacuum of the main condenser 8 and interfere with the operation of the pump 9.

It is desirable that the steam space in the upper portion of the heater 12 be connected to condenser 8 or to the usual air pump so 15 that air and other non-condensable gases may be removed. In the present instance this is done by making the stem 27 hollow so that the upper part of the heater 12 is in direct communication with the condenser 8 20 through conduit 25.

In accordance with the provisions of the Patent Statutes, I have described the principle of operation of my invention, together with the apparatus which I now consider to 25 represent the best embodiment thereof; but I desire to have it understood that the apparatus shown is only illustrative, and that the invention can be carried out by any other means.

30 What I claim as new and desire to secure by Letters Patent of the United States, is:—

1. The combination of a prime mover, a feed water heater comprising tubes through which the water to be heated flows, said 35 water flowing first through the lower tubes and then through the upper tubes, a conduit for leading heating steam from the prime mover to the feed water heater, a conduit for conveying the condensate therefrom, a 40 valve in the last named conduit, and means

controlled by the level of condensate in said feed water heater for operating said valve.

2. In combination, a prime mover, a condenser into which it exhausts, a feed water heater comprising tubes, a pump for taking 45 the condensate from the condenser and pumping it through the tubes of the feed water heater, a conduit for supplying steam to the feed water heater where it is condensed and gives up its heat to the condensate flowing through said tubes, a conduit which connects the feed water heater to the condenser for conveying the condensate of the heating steam to the condenser, and means for maintaining such 50 condensate at a predetermined level in the heater.

3. In combination, a prime mover, a condenser into which it exhausts, a feed water heater comprising tubes, a pump for taking 55 the condensate from the condenser and pumping it through the tubes of the feed water heater, said condensate passing first through the lower tubes and then through the upper tubes, a conduit for supplying steam from the prime mover to the upper portion of the feed water heater, a conduit connected with the bottom of the feed water heater for conveying away the condensate of the heating steam, and a valve in 60 said last named conduit controlled by the level of the condensate of the heating steam in the heater for maintaining such condensate at a predetermined level therein.

In witness whereof, I have hereunto set 75 my hand this 28th day of August, 1918.

FREDERICK SAMUELSON.
